STORAGE DEVICE FOR BRUSHES

Ross W. Hill, Detroit, Mich.

Application February 20, 1958, Serial No. 716,335

1 Claim. (Cl. 206—15.1)

This invention relates to storage devices for brushes and, more particularly, to such a device containing a suitable thinner such as turpentine in which the bristles of the brushes may be immersed for temporary or extended periods of time.

Brushes such as those used in painting, varnishing and the like are normally immersed for periods of time in a suitable thinner, such as turpentine, in order to clean them for subsequent use, and to maintain them as soft as possible. Normally, such brushes are placed in a jar, pail, can or other suitable container in such a manner that the weight of the brush is imposed on the bristles thereof causing them to bend during the soaking period. This is undesirable inasmuch as a brush having straight bristles is most effective in smoothly and accurately applying paint or varnish to a surface. Moreover, since such brushes conventionally include a plurality of bristles embedded in a base of vulcanized rubber or other suitable materials which deteriorate when soaked with such thinners as normally employed for the above purpose, it is important that the level of the thinner in the container does not reach the bristle base so as to soak the latter, while yet completely soaking the bristles to prevent hardening of the paint, varnish or the like therein.

These problems are particularly acute with respect to commercial painters, although not limited thereto, because such painters normally use a plurality of brushes of different sizes for painting large surfaces and for doing trim or finish work. When brushes having varying lengths of bristles are used, it will be apparent that they all cannot rest on the bottom of a container with the bristles thereof immersed to an optimum extent in the thinner without some brush having the bristle base thereof completely soaked with the thinner. Moreover, and as aforementioned, it is desirable that the brush bristles be suspended above the bottom of the container.

Therefore, it is a general object of this invention to provide a storage device for brushes of the type having bristles suitably embedded in a base secured to a handle, and characterized by the fact that vertically adjustable support means is provided for any given brush whereby the latter may be suspended with its bristles out of contact with the bottom of the storage container.

It is yet another object of this invention to provide a storage container of the type aforementioned which is relatively compact, and in which a plurality of brushes of varying sizes may be supported out of contact with the container.

It is yet another object of this invention to provide a storage container of the type aforementioned comprising a vertically adjustable brush support on which a given brush may be suspended substantially vertically in order to maintain the bristles thereof out of contact with the container, and secure optimum immersion of the bristles without soaking the bristle base.

Moreover, it is yet another object of this invention to provide a storage container for brushes of a type aforementioned in which a plurality of brushes of varying

2

sizes can be stored either dry or with a liquid thinner for a long period of time without damaging the bristles.

These and other objects of this invention will become more fully apparent hereinafter as the description of the invention proceeds, and reference is made to the following drawings in which:

Figure 1 is a top plan view of a preferred form of the storage device of this invention with the lid or cover thereof removed;

10 Figure 2 is a sectional view taken on line 2—2 of Figure 1;

Figure 3 is an enlarged sectional view of a portion of the storage device shown in Figure 2, and particularly disclosing a representative support mechanism for the 15 brushes;

Figure 4 is an enlarged perspective view of the structure of Figure 3;

Figure 5 is a transverse sectional view through the storage device showing the latter equipped with a suitable lid or cover.

Referring now to the drawings, there is shown a rectangularly shaped container 2 comprising four wall panels joined together to form a side wall 4, and which side wall is secured to the bottom 6 of the container. Although the container may be of other shapes, the rectangular configuration shown is preferred inasmuch as maximum utilization of the space thereof can be made in storing brushes. A plurality of brush support mechanisms indicated generally at 8, 10, 12 and 14 are spaced 30 along the major axis of the preferred container, and are adapted to adjustably vertically support a plurality of paint brushes and the like of varying sizes out of contact with the container, and in a position in which optimum immersion of the brush bristles will be obtained 35 without subjecting the bristle base to the soaking action of the thinner in the container.

As shown particularly in Figure 1, the support mechanisms 8 and 10 may be adapted to removably and adjustably mount thereon one or two brushes, while the support mechanisms 12 and 14 are adapted to similarly support anywhere from one to four brushes. Naturally, any desired number of brush support mechanisms may be employed with a given container subject only to the size of the latter and the brushes to be stored therein. In any event it is contemplated within the scope of this invention to provide a storage container which is large enough so that a range of brush sizes corresponding to those normally required during a painting operation, for example, may be stored in the same container. Thus, 50 the support mechanisms 8 and 10 are adapted to mount the larger brushes, while support mechanisms 12 and 14 are adapted to support progressively smaller brushes.

Referring now more particularly to Figures 3 and 4, the detailed structure of the support mechanism 8 will be described. The support mechanism 8 may be seen to be comprised of a thin support panel 16, preferably but not necessarily formed of sheet metal, which extends transversely across the major axis of the container within the interior of the latter, and having flanges 18 formed at the ends thereof suitably secured to the interior opposite wall portions of the container. It will be noted that the bottom edge of the support panel is spaced above the bottom of the container, which will be the case with all support panels utilized in the container, so that the latter 60 may be readily filled with and emptied of liquid thinner. However, if desired, the respective support panels could be sealed to the bottom of the container in order to compartmentalize the latter for special situations in which one or more brushes or groups of brushes are being used with different colors of paint or different types of varnishes which it is undesirable to mix in the thinner. In any event, the support panel 16 is provided with an elong-

gate vertical slot 20 substantially at its mid point, although this slot may be located closer to either or both ends of the panel or any number of slots may be used in the panel within reason, as will be apparent hereinafter with reference to the support mechanisms 12 and 14.

The adjustable mounting structure of the support mechanism 8 comprises a thin metal plate, preferably but not necessarily sheet metal, which is bent upon itself to form the side walls 24 and 26 projecting from the juncture or bead 28 to embrace the opposite sides of the support panel 16. Abutment of the juncture or bead 28 with the upper edge of the support panel 16 insures that the mounting plate will not descend too far into the interior of the container 2. Suitable fastener means 30, herein shown to be a bolt and cooperating nut, passes through aligned apertures in the walls 24 and 26 of the plate and the elongate slot 20 in the support panel 16. From the above description, it will be obvious that the fastener means 30 can be loosened to permit any desired vertical adjustment of the mounting plate structure relative to the support panel 16. Brackets 31 secured to the panel 16 embrace the mounting plate structure as shown to maintain the latter in substantially vertically sliding engagement with the panel 16.

Secured to the wall portions 24 and 26 of the mounting plate are horizontally aligned mounting or hanger means, herein shown to be brackets 32, on which a brush is adapted to be removably mounted. Each of the brackets 32 comprises a main body portion 34 fixedly secured to its associated wall portion of the mounting plate, an upper horizontally extending flange or wall portion 36 terminating in a vertically upstanding post 38 adapted to receive a suitable keeper 40 secured to the handle of a paint brush and herein shown specifically to be a substantially U-shaped staple. Moreover, another horizontally extending flange 42 extends from the lower end of the main body portion 34 of each bracket and terminates below the post 38.

The brushes indicated generally at 44 may, for purpose of illustration, be conventional and readily commercially available paint brushes comprising a plurality of bristles 46 suitably embedded or secured in a bristle base of vulcanized rubber, or other suitable material, which is secured to the lower end of the wood handle 48 by means of a metal band 50 having its lower edge crimped to the bottom of the bristle base while suitable means, such as tacks or nails, secure the upper portion of this band to the lower end of the handle 48. The keeper means 40, such as the U-shaped staple shown, is embedded in the lower portion of the handle above the metal band 50.

The aforementioned staple is adapted to receive the post 38 of the mounting bracket and to rest upon the upper horizontal shoulder 36 to suspend the brush in the container. At the same time, the lower horizontal flange or projection 42 of the mounting bracket forms an abutment member engageable with the metal band 50 of the brush to retain the latter in a substantially vertical position. The upper horizontal shoulder or flange is of substantial width so as to cooperate with the base of a U-shaped staple on the brush to prevent substantial pivoting action of the brush in a plane parallel to the support panel 16. Obviously, the lower flange or abutment member 42 will prevent the brush, or more specifically the bristles thereof, from wiping against any portion of the support mechanism 8.

From the above description, it will be apparent that the support mechanisms 12 and 14 likewise include a single support panel corresponding to the support panel 16, but have two laterally spaced elongate slots for cooperation with the vertically adjustable brush mounting structure. Inasmuch as these structures will be identical to that previously described, it is not considered necessary to repeat this description.

Therefore, any desired number of support mechanisms may be employed with a container of suitable size to

mount therein a plurality of brushes. Such a construction may be employed to great advantage as a dry storage device for brushes which no longer need to be soaked in a liquid thinner and, during such storage, the bristles of the respective brushes will be maintained out of engagement with any portion of the container or its respective support mechanism. To this end, it is only necessary to adjust a respective mounting plate relative to its support panel until the bristles of a particular size brush will be suspended above the bottom of the container. Moreover, a suitable number of support mechanisms in which the mounting plates thereof are suitably vertically adjusted may be employed with a single container to house and store a plurality of brushes of varying sizes.

When it is desired to store brushes of different sizes immersed in a liquid thinner within the container, the structure of this invention has the additional advantage of maintaining the bristles of each brush immersed to an optimum extent within the thinner while preventing the bristle base from becoming soaked with the thinner, thereby avoiding the deteriorating action which usually follows. For example, the level of a liquid thinner within the container is indicated at 52 in Figure 2. The brushes mounted, respectively, on the support mechanisms 8 and 10 represent commercially available brushes of different sizes which will demonstrate this aspect of the invention.

In such brushes which are commercially available, the distance between the lower edge of the metal band 50 corresponding to the bottom of the bristle base and the portion of the handle on which the keeper or hanger 40 is secured will vary. The mounting staple is, of course, placed in the same general position in the lower handle portion of the various brushes inasmuch as it will interfere with the handling of the brush very little in this position, and this portion of the handle is large enough to receive it without cracking the handle. Moreover, from a manufacturing standpoint, it is wholly undesirable to measure the distance from the bottom of the metal bands of each brush to a point on the handle thereof where a staple or other hanger or keeper means may be placed in order to make the aforementioned spacing equal from brush to brush. Thus, it will be seen that the brush on support mechanism 10 must be mounted lower than the brush on support mechanism 8 in order to dispose the bottom of the bristle base just slightly above the level of the liquid thinner 52. With the brushes so vertically suspended, the bristles thereof are subjected to a complete soaking to remove the paint, varnish or the like therefrom while preventing soaking and consequent deterioration of the bristle base.

At this juncture it should be noted that the preferred embodiment of the invention disclosed above is merely for illustrative purposes, and is in no way intended to limit the scope of this invention. In particular, the support mechanisms and particular mounting brackets and keeper staples may take many and various forms. For example, the elongate slot 20 in the support panel 16 could be formed in the wall portions 24 and 26 of the mounting plate, while the fastener passes therethrough in an aligned aperture in the support panel 16. In either case, freedom of relative movement between the mounting plate and support panel is achieved upon loosening of the fastener means. Still further, the specific bracket structure disclosed may take many other forms among which are those disclosed in my co-pending application S.N. 716,336, filed February 20, 1958, and entitled, Support For Liquid Applicator.

In Figure 5, the container 2 is shown with a suitable cover 54 which is adapted to be secured in any suitable manner to the container, and is provided with a carrying handle 56. A gasket or sealing member 58 carried at the edge of cover 54 seats on a continuous shoulder 60 on container 2 to sealingly enclose the interior of the container.

I claim:

A storage device for brushes of the type having a plurality of bristles held in a bristle base secured to the lower end of a handle, said device comprising a container formed of a side wall and bottom joined together for retaining a liquid thinner therein, a plurality of spaced panels fixed to the container side wall and extending across the interior of said container above the bottom of the latter, a vertically elongate slot in each of said panels, a support plate for each of said panels comprising spaced walls embracing a respective panel, selectively engageable fastener means extending between the spaced walls of each support plate and through the slot of the respective panel for independently adjustably slidably vertically positioning said plates relative to the level of the liquid in and the bottom of said container, horizontally aligned bracket means on the walls of each of said support plates,

said bracket means comprising a hook-shaped vertical load supporting portion and a lateral projection therebelow, said portion and projection being spaced from said panels and engageable with said brush to maintain the latter suspended substantially vertically.
